(57) **CLAIM**

The ornamental design for a rocket stove, as shown and described.

DESCRIPTION

FIG. 1 is a front, right, and top perspective view of a rocket stove, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a first part of a leg; and,

FIG. 10 is a partial enlarged view of an area labeled 10 in FIG. 1 comprising a second part of the leg.

The broken lines shown in the drawings are included for the purpose of illustrating portions of the rocket stove that form no part of the claimed design.
